UNITED STATES PATENT OFFICE.

EMIL BEHRINGER, OF BROOKLYN, NEW YORK.

INTERNAL REGENERATIVE COOLER.

1,261,476.

Specification of Letters Patent.

Patented Apr. 2, 1918.

Application filed May 8, 1917. Serial No. 167,181.

To all whom it may concern:

Be it known that I, EMIL BEHRINGER, a citizen of the United States, residing in Brooklyn, in the county of Kings and State 5 of New York, have invented certain new and useful Improvements in Internal Regenerative Coolers, of which the following is a specification.

This invention relates to heat exchanging 10 devices or coils, particularly to regenerative coolers for milk and more particularly to elbow connections therefor.

The main object of the invention is to improve generally the construction of coolers 15 of this sort.

Other objects are to provide coolers which may be quickly and easily assembled, taken apart, and cleaned; which may be constructed of thin lightweight material and in 20 as many or few sectors as desired and which will be liquid tight and adapted for contraction and expansion.

Another object is to provide an easily assembled cooler comprising pipes connected 25 by elbow members, the parts of each elbow member being firmly held together by means of a single bolt without the pipes being threaded at all.

These and other objects will appear as the 30 description proceeds; and it is noted that various changes may be made in the construction without departing from the scope of the invention as claimed.

In the accompanying drawing, showing 35 by way of example, one of many possible embodiments of this invention:

Figure 1 is a side elevation of a bank of coils fitted with my improved elbow connection;

40 Fig. 2 is a longitudinal sectional view, partly in elevation, showing, on a larger scale, the separated parts of the elbow connection and cooling tubes;

Fig. 3 is a side elevation, partly in section, showing the elbow connection and cooling tubes assembled; and

Fig. 4 is a perspective view of one of the heads for supporting the tubes and connections.

50 The improved cooler comprises outer tubes 10, inner tubes 11 concentric therewith and elbow connections 12 all supported by the supporting heads 14 suitably secured together by short bolts 15 engaging in the slots 16 and 18 (Fig. 4) of the flanges of the heads 14.

The outer tubes 10 are received in countersunk openings 19 (Figs. 2 and 3) of the heads 14 and held liquid tight therewith by packings 20. The outer face of the head 14 60 is provided with an annular groove 21 in which are received the packing 22 and the inner edge of the inner chamber ring 24, said ring 24 forming with said head 14 an annular inner chamber 25, communicating 65 with the interior of the two outer tubes 10.

Each inner tube 11 passes entirely through the outer tube, the head 14 and one of the circular openings 26 of the inner chamber ring 24, and is rendered liquid tight in such 70 opening 26 by the packing 28 in the countersunk groove 29 of said opening.

Each outer chamber ring 30 is provided with a pair of tubular projections 31 received in said countersunk grooves 29, and receiving the ends of the inner tubes 11. The outer face of the outer chamber ring 30 is provided with an annular groove 32 in which is received a packing 34 and the inner edge of the chamber cap 35, said cap being provided with a central opening 36.

The head 14 is provided with a central bore 38 surrounded by a deep outwardly projecting boss 39. The inner chamber ring 24 is likewise provided with a central bore 40 85 surrounded by an inwardly projecting boss 41 between which and the boss 39 a packing 42 is pressed. The outer chamber ring 30 is provided with a central opening 44, surrounded by an annular shoulder 45. A packing 48 is disposed against said shoulder 45.

The outer tubes 10 are provided near their ends with opposed bolt engaging lugs 49 engaging the head of a bolt 50 passing through said central bores and central openings and having threaded connection with a nut 51 pressing against said packing 48 and holding said rings, said head and the outer tubes together. The cap 35 is held in place by the outer nut 52 pressing the packing 54 against the cap as shown. By this arrangement the parts of the elbow connections are firmly held together and to the tubes by a single bolt which insures ease of assembling and taking apart and economy 105 of construction.

It is, of course, understood that instead of the lugs 49, other equivalents, such as grooves or the like, could be milled or otherwise provided on the ends of the outer tubes 110 for engagement by the bolt heads.

Leaking of the liquid at the bolt connec-

tions is prevented by the packings 42, 48 and 54, and the inner chamber 25 and the outer chamber 55 are thus rendered liquid tight at their inner parts.

5. The lowest head 58 at one end of the lowest outer pipe 10 is made to receive only one outer and inner tube as is obvious. Each pile of heads is supported on a suitable base 59 (Fig. 1).

10. When it is desired that heat be transferred from one liquid to another, one of the liquids is passed through each tube, suitable connections being provided at the ends of the coils. The direction of relative 15 flow and the relative disposal of the warmer liquid may be determined by the circumstances of each case.

The whole cooler may be easily taken apart for cleaning. It is only necessary to 20 remove the nuts 51 and 52 and to slide off the various parts from the bolt 50, and separate them as indicated in Fig. 2. For assembling the cooler, the reverse operation takes place.

25. By providing the slots 16 and 18 (Fig. 4), the heads may be quickly assembled or taken apart, and the slots being placed parallel to the axis of the pipes, permit relative movement between the heads 14 30 when the pipes expand unequally.

I claim:

1. In combination, an elbow member provided with a pair of chambers; a pair of outer tubes terminating in one of said chambers; a pair of inner tubes passing through said outer tubes and terminating in the other of said chambers; and means passing centrally through said elbow member and engaging said outer tubes for locking said 35 elbow member to said outer tubes.

40. 2. In combination, an elbow member provided with a pair of chambers; a pair of outer tubes terminating in one of said chambers; a pair of inner tubes passing through said outer tubes and terminating in the other of said chambers; and a single bolt passing through said elbow member and engaging said outer tubes for locking said 45 elbow member and said outer tubes together.

50. 3. In combination, a plurality of heads disposed one above the other and comprising contacting flanges, each flange being provided at opposite ends with a slot adjacent respectively to a slot of the adjacent head; and clamping bolts passing through said perforations and recess for clamping the heads together; and tubes supported by said heads.

55. 4. In combination, a pair of outer tubes; a pair of inner tubes passing through the outer tubes; a head provided with openings receiving the ends of the outer tubes; a cap; means disposed between the cap and the head for receiving the ends of the inner tubes and 60 forming with the head and the cap inner and outer chambers respectively establishing communication between the outer tubes and between the inner tubes; a bolt passing through said head, means and cap, and locking them together.

tubes and forming with the head and the cap inner and outer chambers respectively establishing communication between the outer tubes and between the inner tubes; and a bolt passing through said head, means 70 and cap, and locking them together.

5. In combination, a pair of outer tubes provided with shoulders; a pair of inner tubes passing through the outer tubes; a head provided with openings receiving the 75 ends of the outer tubes; a cap; means disposed between the cap and the head for receiving the ends of the inner tubes and forming with the head and the cap inner and outer chambers respectively establishing communication between the outer tubes and between the inner tubes; and a bolt passing through said head, means and cap, and locking them together and engaging 80 said shoulders.

6. In combination, a pair of outer tubes; a pair of inner tubes passing through the outer tubes; a head provided with openings receiving the ends of the outer tubes; a cap; means disposed between the cap and the head for receiving the ends of the inner tubes and the 90 head for receiving the ends of the outer tubes and forming with the head and the cap inner and outer chambers respectively establishing communication between the outer tubes and between the inner tubes; a bolt passing through said head, means and cap, and locking them together; and packings surrounding said bolt and disposed between said means and said head.

7. In combination, a pair of outer tubes; a pair of inner tubes passing through the outer tubes; a head provided with openings receiving the ends of the outer tubes; a cap; means disposed between the cap and the head for receiving the ends of the inner tubes and the 100 head for receiving the ends of the outer tubes and forming with the head and the cap inner and outer chambers respectively establishing communication between the outer tubes and between the inner tubes; a bolt passing through said head, means and cap, and locking them together; a nut on said bolt clamping said means to said head; and a packing between said nut and said means.

8. In combination, a pair of outer tubes; a pair of inner tubes passing through the outer tubes; a head provided with openings receiving the ends of the outer tubes; a cap; means disposed between the cap and the head for receiving the ends of the inner tubes and the 110 head for receiving the ends of the outer tubes and forming with the head and the cap inner and outer chambers respectively establishing communication between the outer tubes and between the inner tubes; a bolt passing through said head, means and cap, and locking them together; a nut on said bolt clamping said means to said head; and a nut on said bolt clamping said cap to said means.

9. In combination, a pair of outer tubes; an inner tube disposed concentrically in each 120

- outer tube; a head provided with openings receiving the ends of the outer tubes; an inner ring disposed on said head and forming an inner chamber establishing communication between the outer tubes, said ring being provided with a pair of openings receiving the end portions of the inner tubes; an outer ring receiving the ends of the inner tubes; a cap on the outer face of the outer ring and forming an outer chamber establishing communication between the inner tubes; and a bolt passing through said cap, rings and head and clamping them together and to the outer tubes.
15. In combination, a pair of outer tubes provided with opposed lugs; an inner tube disposed concentrically in each outer tube; a head provided with countersunk openings receiving the ends of the outer tubes, and a central bore surrounded by an outwardly extending boss; an inner chamber ring disposed against the outer face of the head and forming therewith an inner chamber establishing communication between the outer tubes, said ring being provided with a pair of openings snugly receiving the ends of the inner tubes, and with a central bore surrounded by an inwardly extending boss; an outer ring provided with a pair of eccentric tubular projections receiving the ends of said inner tubes, and with a central opening surrounded by a shoulder; a cap engaging over the outer face of the outer ring and provided with a central opening; a bolt engaging said lugs and passing through said bores and central openings; a nut on said bolt and engaging said shoulder; and a nut on the bolt engaging said cap.
11. In combination, a plurality of tubes; heads supporting said tubes and each provided with slots disposed parallel to the tubes; and bolts disposed in said slots and securing said heads together.
12. In combination, a plurality of tubes; heads supporting said tubes and each provided with longitudinal slots; and bolts disposed in said slots and securing said heads together and permitting relative movement between the heads and relative expansion of the tubes.
13. In combination, a plurality of tubes; superposed heads supporting said tubes and each provided with flanges provided with longitudinal slots, the slots of one head registering with slots of the adjacent head; and bolts disposed in said slots and securing said heads together and permitting relative movement between the heads and relative expansion of the tubes.
14. In combination, a plurality of tubes; heads supporting said tubes and each provided with flanges provided with open ended slots disposed parallel to the tubes, the slots of one head registering with slots of the adjacent head; and bolts disposed in said slots and securing said heads together.
15. In combination, a plurality of tubes; heads supporting said tubes and each provided with flanges provided with longitudinal open ended slots disposed longitudinally of the tubes; and bolts disposed in said slots and securing said heads together.
16. In combination, a plurality of tubes; heads supporting said tubes and each provided with slots, the slots of one head registering with slots of the adjacent head; and bolts disposed in said slots and securing said heads together and permitting relative movement between the heads in a direction longitudinal to the tubes and expansion of the tubes.
17. In combination, a plurality of tubes; superposed heads supporting said tubes and each provided with flanges provided with longitudinal open ended slots, the slots of one head registering with slots of the adjacent head; and bolts disposed in said slots and securing said heads together and permitting relative movement between the heads and relative expansion of the tubes.
18. In combination, a pair of outer tubes provided with opposed lugs; an inner tube disposed concentrically in each outer tube; a head provided with openings receiving the outer tubes; an inner chamber ring pressed against said head and forming an inner chamber therewith and provided also with a pair of openings receiving the ends of the inner tubes; an outer chamber ring disposed against the inner chamber ring and forming an outer chamber therewith establishing communication between the inner tubes; a cap on the outer chamber ring; and a bolt engaging said lugs and passing centrally through said head, rings and cap and clamping them together.
